NEBULIZER

Lawrence H. Zahn, Mountainside, N. J., assignor
to Ciba Pharmaceutical Products, Incorporated,
Summit, N. J., a corporation of New Jersey

Application March 8, 1951, Serial No. 14,414

Term of patent 14 years

(Cl. D83—1)

To all whom it may concern:

Be it known that I, Lawrence H. Zahn, a citizen
of the United States, residing at Mountainside,
State of New Jersey, have invented a new, orig-
inal, and ornamental Design for Nebulizer, of
which the following is a specification, reference
being had to the accompanying drawing, forming
a part hereof.

Fig. 1 is a front elevational view of a nebuli-
zer showing my new design;

Fig. 2 is a side elevational view taken at right
angle to the view of Fig. 1;

Fig. 3 is a top plan view of the nebulizer shown
in Fig. 1; and

Fig. 4 is a bottom plan view of the nebulizer
as shown in Fig. 2.

The back and other side of the nebulizer are
identical in appearance to the front and side dis-
closed.

I claim:

The ornamental design for a nebulizer, as
shown and described.

LAWRENCE H. ZAHN.
